LAWN EDGER

John D. Beinert, Babylon, N.Y., assignor to International Patent Research Corp., New York, N.Y., a corporation of New York

Filed Nov. 15, 1966, Ser. No. 4,677

Term of patent 7 years

(Cl. D40—1)

FIG. 2

FIG. 1

FIG. 3

FIG. 1 is a three-quarter perspective view of a lawn edger, showing my new design;

FIG. 2 is a front elevational view thereof; and

FIG. 3 is a side elevational view thereof taken from the right hand side of FIG. 1.

The handle has been broken away in FIG. 3 to indicate intermediate length.

The dominant portions of the design are those shown in solid lines.

I claim:

The design for a lawn edger, as shown and described.
